DELIVERY CONTROL DEVICE FOR CIGARETTE MAKING MACHINES

Filed Sept. 25, 1919

Patented June 21, 1927.

1,633,377

UNITED STATES PATENT OFFICE.

WILLIAM F. GRUPE, OF HUDSON HEIGHTS, NEW JERSEY, ASSIGNOR TO ENDLESS BELT CORPORATION, INC., A CORPORATION OF NEW YORK.

DELIVERY-CONTROL DEVICE FOR CIGARETTE-MAKING MACHINES.

Application filed September 25, 1919. Serial No. 326,289.

This invention relates to delivery control devices for cigarette making machines.

An object of the invention is the provision of means in a cigarette making machine for detecting the condition of abnormal operation.

A further object of the invention is to provide means for detecting the condition of malformation of the cigarette product as well as any interruption in the production of the cigarette.

In the most preferred forms of the invention the detecting means is responsive to any undue departure of the product from its normal path as well as to the conditions of malformation and interruption in the production of the machine.

Such most preferred form of the invention of the type applicable for cigarette making machines producing the cigarette in the form of the so-called cigarette rod, comprises detecting means including an element extending adjacent the normal path of the cigarette rod within predetermined limits and mounted to be displaced upon the condition to be detected, such element controlling a member having an imperforate body portion and provided with an opening of predetermined contour corresponding to such predetermined limits, a pin adapted to enter such opening under conditions of normal production, a block carrying such pin, a latch normally held by such pin and constructed to be released under the condition of abnormal production of the machine, such latch when in its released position being arranged to operate the brake of the cigarette machine or otherwise retard or stop the operation of the machine and thereby discontinue or interrupt the feeding parts of the cigarette machine.

In such usual type of cigarette making machine it is advantageous to mount such pin on the reciprocating slide disposed on the bed of the machine, thereby simplifying the arrangement and operation of the parts of my delivery control device and effecting automatic retardation or stopping under the condition of interruption of the normal production of the machine.

The invention is applicable as an attachment to existing, approved cigarette making machines, although it will be understood that the invention is also applicable to be

incorporated in cigarette making machines as a whole.

Further features and objects of the invention will be more fully understood from the following description and the accompanying drawings, in which

Fig. 1 is a top plan view of the delivery end of an approved type of cigarette making machine provided with one form of my invention;

Fig. 2 is a side elevation of one form of detecting device;

Fig. 3 is a top plan view of Fig. 2;

Fig. 4 is a top plan view of a carrier block showing the detecting pin in normal position;

Fig. 5 is a side elevation of Fig. 4;

Fig. 6 is a top plan view similar to Fig. 4 but showing the detecting pin in displaced position under an abnormal condition;

Fig. 7 is a side elevation of Fig. 6;

Fig. 8 is an end elevation of Fig. 4; and

Fig. 9 is a sectional elevation on line 9—9 of Fig. 4.

Referring to the drawings, and particularly to Fig. 1, the cigarette making machine 1 is of any suitable approved type provided with the usual feeding devices combined with the tube belt passing over the pulley 2 and coacting with the usual forming shoe whereby the strip of paper and tobacco fed thereon are formed into the cigarette rod indicated at 3, delivered into flared delivery tube 4 and cut into individual length by the rotating knife, or otherwise, and eventually delivered upon the traveling belt 6.

Such cigarette forming mechanism is of the usual or any other approved specific construction and accordingly has not been illustrated in detail nor referred to otherwise in particular herein.

On the bed 10 of the cigarette machine 1 is indicated the usual cigarette cutting mechanism designated generally 11 controlling the rotary knife 12 and comprising the slide 13 carrying the knife 12. Such slide 13 is usually connected by the connecting rod 14 with the wheel 15 by the adjustable cam 16 whereby upon rotation of the wheel 15 the slide 13 is reciprocated between suitable guides on the face of the bed 10.

To a face 17 of the slide 13 I have attached the plate 18 carrying the block 19 in which is mounted the pin 20 in such man-

ner as set forth more particularly herein-after coacting with suitable mechanism controlling the operation of the cigarette making machine whereby upon the condition of 5 malformation of the cigarette rod 3, or departure of the cigarette rod from its normal path beyond predetermined limits or other irregularity in the production of the cigarette rod, the cigarette machine will be retarded or brought to rest.

As indicated in Fig. 1, such pin 20 controls the shifter 21 or clutch handle of the usual clutch control mechanism of the machine and accordingly upon the condition of 15 irregularity of cigarette production, the machine is brought to rest.

As is indicated in Figs. 4 to 7, inclusive, the block 19 is provided with the substantially horizontal perforation 22 loosely receiving the pin 20, said pin 20 at its rearward portion 23 carrying the keeper 24, and normally tensioned by the expansive spring 25 to be held in the position shown in Figs. 4, 5 and 9.

25 The rear face of the block 19 is cut away at 26 (see Fig. 4) to provide a substantially vertically extending slot in which is loosely disposed the latch member 27 provided at its upper end with the recess 28 in which is 30 loosely received the guide pin 29, see Fig. 5, having the head 30 supported in the angle plate 31 mounted on the upper face of the block 19. Such latch member 27, see Fig. 8, is provided with the horizontal slot 32, see 35 Fig. 5, receiving the keeper 24 when the pin 20 is in its normal position with respect to the block 19.

The latch member 27 is retained within the slot 26 by means of the plate 33. The 40 plate 33 is provided with the opening 34, see Fig. 8, to provide clearance for the movement of the keeper 24 when releasing the latch member 27 and to permit the return of the keeper 24 within the slot 32 of the latch member 27. The release of the latch member 27 may be aided by means of the expansive spring 35 shown coiled about the upper portion of the guide pin 29.

45 Disposed in a certain relation with the cigarette rod when traversing its normal path beyond the tube belt, I have provided suitable means 36 responsive to the conditions of malformation or interruption or departure beyond predetermined limit of the cigarette rod 3.

In the specific embodiment of the invention shown in Figs. 2 and 3, such responsive means 36 comprises an upper jaw member 37 having a detecting face plate 38 extending 50 above the normal path of the cigarette rod at a predetermined clearance. Such responsive means 36 may further comprise the lower jaw member 39 having a similar detecting face plate 40 related similarly on the 55 lower side of the cigarette rod 3. Such up-

per jaw member 37 and lower jaw member 39 may be mounted on the common pivot pin 41 tapped in the standard 42 positioned on the bed 10 of the cigarette making machine 1, as indicated in Fig. 1. Each such 70 jaw members 37, 39, extend laterally of the pivot pin 41 and are provided with the imperforate body portion 43, 44, respectively, having the abutting edges 45, 46, adapted to engage one another when the face plates 75 38, 40, are in normal position relative to the cigarette rod 3.

Such body portions 43, 44, are provided with corresponding recesses or cut away portions 47, 48, forming conjointly the opening 49 of predetermined contour and disposed under normal condition of operation of the cigarette machine and normal positions of the face plates 38, 40, with respect to the cigarette rod 3, to permit the pin 20 80 to enter through such opening 49 upon the forward reciprocation of the slide 13 and therewith the block 19 carrying the pin 20, and exit through such opening 49 upon the return reciprocation of the slide 13.

Upon the condition of interruption of normal production of the cigarette rod 3, the jaw member 37, being mounted on its pivot 41 to be biased downwardly, as by being over-weighted at its face plate 38 or by action of a suitable, downwardly tensioning spring 37^a, see Fig. 2, or equivalent, is displaced downwardly, thereby rotating the imperforate body portion 43 within the path of reciprocation of the pin 20, and upon the pin 20 encountering such imperforate body portion 43, is held in its movement in its direction of length against its spring 25, thereby withdrawing the keeper 24 from the slot 32 of the latch member 27 95 as indicated in Figs. 6 and 7, and is thus released and under action of gravity, and of its spring 35, drops and upon the block 19 attaining the position as is indicated in Fig. 5, in its path of reciprocation forwardly 100 of the control rod 60, the latch member 27 encounters and advances the control rod 60 in the direction of the indicated arrow 59, see Figs. 7 and 1, thereby operating the lever 61 and link 62 to throw the regulation 105 shifter or clutch handle 21 to disengage the operating shaft of the cigarette making machine from the power device, or otherwise interrupting the operation of the cigarette machine and thereby bringing to rest the paper feeding mechanism, the cigarette feeding mechanism, the driving mechanism of the tube belt and other desired parts of the cigarette forming mechanism.

To restore the operation of the cigarette making machine, the latch member 27 is returned to its upper position as aforesaid by manually pushing it upwardly at its lower end or by manually pulling it upwardly by 115 grasping the head of its pin 30, which upper 120

position of the latch member 27 is maintained by the keeper 24 being returned into the slot 32 by its spring 25, whereafter the detecting member 37 is held manually by the operator until the cigarette rod 3 passes between the face plates 38, 40, whereupon the machine is in full operation preparatory for detecting any further abnormal condition of operation.

10 It will be noted that the face plates 38, 40 are shown flared divergently to assist reception of the newly formed cigarette rod between the face plates 38, 40.

The spacing between the face plates 38, 40 of the jaws 37, 36, respectively, see Fig. 8, is sufficient to allow for the normal diameter of the cigarette rod, but upon the cigarette rod being malformed of less diameter or upon being burst or the seam of the cigarette rod opening out due to the absence or the depletion of adhesive for binding the seam, the effective "thickness" of the cigarette rod is decreased to a dimension less than the normal spacing between the face plates 38 and 40, the face plate 39 of the jaw 37 is lowered by the action of its spring 37^a, or equivalent, thereby causing its imperforate portion 43 to rise and be moved across the path of reciprocation of the pin 20, and effect the shutting down of the cigarette rod forming mechanism of the cigarette making machine, similarly as described hereinabove.

For simplicity of operation, such jaw members 37, 39 are assembled jointly in the manner of pincers or scissors, the imperforate body portions 43, 44 of the jaw members 37, 39 being disposed vertically in alignment with one another, as appears in Fig. 3, and thereby to effect the substantial engagement between their adjacent faces, as indicated in Fig. 2 and thus provide for the normal spacing from one another in correspondence to the thickness of the cigarette rod.

As appears above, but a single jaw member may be employed for the detection of the condition of interruption in the production of the cigarette rod, namely, the jaw member 37, but the operation of detection generally of all abnormal or irregular operation of the machine is facilitated by the use of the plurality of jaw members disposed on opposite sides of the cigarette rod.

55 Whereas I have described my invention by reference to specific forms thereof, it will be understood that many changes and modifications may be made without departing from the spirit of the invention, as defined by the appended claims.

I claim:

1. A cigarette making machine comprising a cigarette-rod-forming mechanism including a forming shoe, a pulley for locating a tube belt in operative relation through

said forming shoe, means for imparting movement of the tube belt over said pulley and through said forming shoe, a shaft for driving said cigarette making machine including said tube belt movement imparting means and a clutch for said shaft, means for actuating said clutch, said clutch actuating means being disposed relative to the normal path of a cigarette-rod formed by said cigarette-rod-forming mechanism to be ineffective under the condition of the normal formation of a cigarette-rod and to be effective for actuating said clutch under the condition of abnormal formation of a cigarette-rod.

2. A cigarette making machine comprising a cigarette-rod-forming mechanism including a forming shoe, a pulley for locating a tube belt in operative relation through said forming shoe, means for imparting movement of the tube belt over said pulley and through said forming shoe, a shaft for driving said cigarette making machine including said tube belt movement imparting means and a clutch for said shaft, means for actuating said clutch, said clutch actuating means comprising a pivoted member disposed relative to the normal path of a cigarette-rod formed by said cigarette-rod-forming mechanism to be disposed at a predetermined clearance from said normal path and thereby rendered ineffective under the condition of the normal formation of a cigarette-rod and rendered effective for actuating said clutch under the condition of abnormal formation of a cigarette-rod.

3. A cigarette making machine comprising a cigarette-rod-forming mechanism including a forming shoe, a pulley for locating a tube belt in operative relation through said forming shoe, means for imparting movement of the tube belt over said pulley and through said forming shoe, a shaft for driving said cigarette making machine including said tube belt movement imparting means and a clutch for said shaft, means for actuating said clutch, said clutch actuating means including a pivoted member having an arm portion disposed relative to the normal path of a cigarette-rod formed by said cigarette-rod-forming mechanism to be ineffective under the condition of the normal formation of a cigarette-rod and to be effective for actuating said clutch under the condition of abnormal formation of a cigarette-rod, said pivoted member further including a body portion provided with an opening, the remainder of said body portion being imperforate.

4. In a cigarette making machine, the combination of a driving shaft, a clutch for said driving shaft, lever means controlling said clutch, said lever means comprising an arm, mechanism for forming a cigarette-rod and driven by said driving shaft, severing means for the cigarette-rod formed by

4
said cigarette-rod-forming mechanism, a 50 slidingly mounted block carrying said severing means, cam means for reciprocating said sliding block, said cam means being actuated by said driving shaft, and means co-operating with said arm for operating said clutch, said arm co-operating means comprising a member carried and reciprocated by said slidingly mounted block, said arm co-operating means further comprising a movable second member disposed relative to the normal path of the cigarette-rod formed by said cigarette-rod-forming mechanism to be ineffective under the condition of the normal formation of a cigarette-rod and to be effective for actuating said arm under the condition of abnormal formation of a cigarette-rod.

5. In a cigarette making machine, the combination of a driving shaft, a clutch for said driving shaft, lever means controlling said clutch, said lever means comprising an arm, mechanism for forming a cigarette-rod and driven by said driving shaft, severing means for the cigarette-rod formed by said cigarette-rod-forming mechanism, a slidingly mounted block carrying said severing means, cam means for reciprocating said sliding block, said cam means being actuated by said driving shaft, and means co-operating with said arm for operating said clutch, said arm co-operating means comprising a member carried and reciprocated by said slidingly mounted block, said arm co-operating means further comprising a movable second member including an arm portion and a body portion, said arm portion being disposed relative to the normal path of the cigarette-rod formed by said cigarette-rod-forming mechanism to be ineffective under the condition of the normal formation of a cigarette-rod and to be effective in co-action with said first-named member of said clutch operating means for actuating said arm under the condition of abnormal formation of a cigarette-rod.

6. In a cigarette making machine, the combination of a driving shaft, a clutch for said driving shaft, lever means controlling said clutch, said lever means comprising an arm, mechanism for forming a cigarette-rod and driven by said driving shaft, severing means for the cigarette-rod formed by said cigarette-rod-forming mechanism, a slidingly mounted block carrying said severing means, cam means for reciprocating said sliding block, said cam means being actuated by said driving shaft, and means co-operating with said arm for operating said clutch, said arm co-operating means comprising a pointed member carried by said slidingly mounted block, said arm co-operating means further comprising a movable second member including an arm portion and a body portion, said body

portion being provided with an opening for normally receiving said pointed member and thereby render said arm co-operating means ineffective under the normal formation of a cigarette-rod by said cigarette-rod forming mechanism, said body portion being otherwise imperforate, said arm portion being disposed relative to the normal path of a cigarette-rod to be displaced under the condition of abnormal formation of a cigarette-rod and thereby move said imperforate portion of said body portion in the path of said pointed member and thereby effect the actuation of said arm and therewith the actuation of said clutch controlling lever means.

7. In a cigarette making machine, the combination of a driving shaft, a clutch for said driving shaft, lever means controlling said clutch, said lever means comprising an arm, mechanism for forming a cigarette-rod and driven by said driving shaft, severing means for the cigarette-rod formed by said cigarette-rod-forming mechanism, a slidingly mounted block carrying said severing means, cam means for reciprocating said sliding block, said cam means being actuated by said driving shaft, and means co-operating with said arm for operating said clutch, said arm co-operating means comprising a member carried and reciprocated by said slidingly mounted block, said member including a base, an element slidably mounted on said base, latch means normally holding said element in a predetermined position, said latch member having a pointed end portion, said arm co-operating means further comprising a movable second member having an arm portion and a body portion, said body portion being provided with an opening, said body portion being otherwise imperforate, said arm portion being disposed relative to the normal path of a cigarette-rod formed by said cigarette-rod forming mechanism to locate said opening in alignment with said pointed member and thus render said arm co-operating means ineffective and under the condition of abnormal formation of a cigarette-rod to be displaced and thereby move said imperforate portion of its body portion in the path of said pointed member and thereby effect the actuation of said arm and therewith the actuation of said clutch controlling lever means.

8. In a cigarette making machine, the combination of a driving shaft, a clutch for said driving shaft, lever means for controlling said clutch, said lever means including an arm, mechanism for forming a cigarette-rod and driven by said driving shaft, severing means for the cigarette-rod formed by said cigarette-rod forming mechanism, a slidingly mounted block carrying said severing means, cam means actuated by said driving shaft for reciprocating said slidingly mount-

ed block and means co-operating with said lever means for operating said clutch, said arm co-operating means comprising a base carried by said slidingly mounted block, an element movably mounted on said base, a latch for normally holding said element in a predetermined position relative to said base and out of operative relation with said arm, said latch having a pointed end portion, a spring normally holding said latch and therewith said element in said predetermined position, said arm co-operating means further comprising a movable second member including an arm portion and a body portion, said body portion being provided with an opening for normally receiving said pointed end portion and thereby render said arm co-operating means ineffec-

tive under the normal formation of a cigarette-rod by said cigarette-rod forming 20 mechanism, said body portion being otherwise imperforate, said arm portion being disposed relative to the normal path of a cigarette-rod to be displaced under the condition of abnormal formation of a cigarette-rod and thereby move said imperforate portion of its body portion in the path of said pointed end portion and thereby effect the release of said latch from said spring and therewith the movement of said element to 30 thereby engage said arm of said clutch controlling lever means.

In testimony whereof I have signed this specification this 24th day of September, 1919.

WILLIAM F. GRUPE.
